UNITED STATES PATENT OFFICE.

SIMON LOUIS BRAUN, OF ANTWERP, BELGIUM.

GLASS-CUTTER.

1,169,714.

Specification of Letters Patent. Patented Jan. 25, 1916.

Application filed May 3, 1912, Serial No. 694,886. Renewed December 20, 1915. Serial No. 67,943.

To all whom it may concern:

Be it known that I, SIMON LOUIS BRAUN, manufacturer, a subject of the King of the Belgians, and resident of 19 Rue du Régent, 5 Antwerp, Belgium, have invented a certain new and useful Glass-Cutter, of which the following is a specification.

My invention relates to a device for cutting glass provided with rowels, the rowels 10 being interchangeable and a stock of them stored in the tool itself. I attain these objects by the mechanism illustrated in the accompanying drawing which represents a front view of the glass cutter and in which:

15 Figure 1 shows the device closed and Fig. 2 the device open.

The glass cutter consists of a plate (1) in tempered steel, copper or any other metal that can be used for the purpose. This plate 20 is fitted with another plate (2) which slides longitudinally upon plate (1). To this purpose plate (1) is provided with buttons (3). These buttons hold the two plates (1) and (2) together while at the same time allowing plate (2) to slide on plate (1). The rowels are placed in a groove cut in plate 25 (1) and are liberated by the sliding of plate (2). The space opened in the groove is sufficiently large to release one of the 30 rowels. In order to prevent plate (2) from sliding too easily, a stop (6) holds plate (2) in the closed position and a certain effort is required to slide it. Plate (1) is also provided on one side with a handle and on 35 the other with a pivot. On this pivot is placed the rowel which protrudes slightly beyond plates (1) and (2). The pivot may be interchangeable and screwed into the plate.

40 To replace a rowel, it is only necessary to

slide the plate (2) from right to left. The rowel which is held on to the pivot by plate (2) then appears before the opening in plate (2). We then have only to turn the instrument over to let the rowel fall out. 45 When this is done another rowel is made to slide out of the groove in plate (1). The fresh rowel is then placed on the pivot, and to fix it it is only necessary to slide plate (2) toward the right. Now as plate (2) is 50 no longer over the opening to the pivot the rowels are held in place and cannot come out. Plate (2) is provided with a slit so that the rowels stored in the tool are visible. Deep cuts are made in plate (2) so that it 55 does not come into contact with the glass breaking indents.

The instrument may be made in steel or any other suitable metal.

I claim:

In a glass cutting tool the combination 60 with a flat metal head having a pin or pivot for supporting a rowel or cutter screwed into its extremity, with a sliding plate movable longitudinally between two positions on the said flat head, the said plate having a hole through which the rowel or cutter supported on the pivot can be removed, when the plate is in the first or non-working position, said plate covering the 65 pivot and retaining the rowel or cutter in place when in the second or working position.

In witness whereof I have hereunto set 70 my hand in the presence of two witnesses.

75 SIMON LOUIS BRAUN.
